UNITED STATES PATENT OFFICE

PHILIP W. DES ROCHES, OF DETROIT, MICHIGAN

REFRIGERATING SYSTEM

Application filed September 9, 1927. Serial No. 218,395.

My invention has for its object to provide a refrigerating system having a valve construction located intermediate the high and low pressure sides of the system that will permit the expansion of the liquefied refrigerant in a plurality of units at rates that will produce the maximum efficiency of the apparatus in the performance of its function of chilling a surrounding medium, or associated object, or material. The invention also provides for insuring the return of the lubricant that is carried from the compressor in the refrigerant, notwithstanding the repeated cycles through which the refrigerant is subjected to in the operations of the system. The lubricant content in the refrigerant is controlled by the valve construction and the lubricant is progressively separated from the liquefied refrigerant by the evaporation of the refrigerant and is introduced into the vaporized refrigerant in subdivided quantities at a uniform rate and at substantially uniform subdivided portions.

The invention also provides for the ready assembly and adjustment of the valve parts and parts that constitute the more sensitive and controlling elements of the valve structure.

The invention may be contained in refrigerating apparatuses which vary in their details, and, to illustrate a practical application of the invention, I have selected an apparatus containing the invention as an example of the various forms of systems that embody my invention, and shall describe it hereinafter. The refrigerating apparatus selected is shown in the accompanying drawings.

Fig. 1 illustrates the parts of the refrigerating apparatus, which is selected as illustrative of the various apparatuses embodying my invention. Fig. 2 illustrates a transverse sectional view of the release valve structure. Fig. 3 illustrates a vertical sectional view of the lubricant separator. Fig. 4 illustrates a section of the valve structure taken on the plane of the line 4-4 indicated in Fig. 2. Fig. 5 is a view of a section of a part of the valve structure shown in Fig. 2 taken on the plane of the line 5-5 indicated in Fig. 2. Fig. 6 is a view of a section of a part of the

valve structure taken on the plane of the line 6-6 indicated in Fig. 2. Fig. 7 illustrates a movable valve member that controls the movement of the liquefied refrigerant from the high pressure side of the system to the low pressure side of the system. Fig. 8 illustrates the valve seat and guide. Fig. 9 illustrates the valve seat and guide retaining member. Fig. 10 illustrates one form of liquid refrigerant and lubricant trapping and separating cup. Fig. 11 illustrates a modified form of the lubricant trapping and separating cup. Fig. 12 illustrates a third form of lubricant trapping and separating cup. Fig. 13 illustrates a means for removing lubricant from the bottom of one of the chilling units of the apparatus. Fig. 14 illustrates a plurality of baffles that may be used in the casing of the float chamber to prevent surging of the refrigerant into the chilling units of the apparatus.

The system which has been selected as an example of the various embodiments of my invention, is a combination of a wet and dry system wherein the liquefied refrigerant is allowed to enter a suitable container, or coils, and be distributed over a heat transmitting surface in order that heat may be absorbed from an associated medium as the liquid is changed to a vapor and, subsequently, as the vapor is allowed to expand in succeeding chilling units. In such a system a vital problem is the separation of the lubricant from the liquefied refrigerant which is carried from the compressor in the refrigerant during the process of liquefying it and, in order to produce this separation, the liquefied refrigerant is flushed through the system to a point where the liquid and the lubricant may be trapped and the liquid may be subsequently vaporized, causing separation of the lubricant. The lubricant is then progressively, and at a uniform rate, introduced into the vapor which is drawn to the compressor during the period in which the compressor is in operation. Thus the invention provides for, not only flushing the liquefied refrigerant through the chilling units, but it, moreover, prevents the liquefied refrigerant from entering into the compressor. It also prevents a continuous stream of

the lubricant from entering the compressor. This will assure that the maximum refrigerating effect producible will be performed only in the chilling units, rather than in the compressor. The chilling effect that is produced in the change, from the liquid to the vapor, to separate it from the lubricant, occurs in one of the chilling units where it is closely associated with the medium that is to be chilled.

It is to be understood, however, that the various features to which the claims are directed, may be utilized in any form of refrigerating system, either a dry evaporative type or a wet evaporative type, or combinations of these systems. Furthermore, by utilizing the controlling elements that embody the invention in a combination of wet and dry evaporative systems, I obtain the advantages of both of the systems and avoid the disadvantages of either of them. This particularly has reference to the heat absorptive power of the system and the control of the lubricant within the refrigerant, and also with respect to the control of the period of the cycle of operations by a pressurestat in place of a thermostat, and as to the quantity of refrigerant used, and the high volumetric capacity of the compressor that is obtained in a wet system, and also as to heat storage in the liquefied refrigerant in a degree corresponding to its quantity.

The refrigerant is operated upon periodically by the compressor to produce liquefaction of the refrigerant that during the preceding operations has become vaporized. As is well known in connection with such apparatuses, the lubricant used in lubricating the parts of the compressor, is carried away from the compressor in the refrigerant which produces deleterious effects on the refrigerant and greatly diminishes the efficiency of the apparatus. These injurious results increase as the cyclic operations are performed owing to the rapid increase of the lubricant content within the refrigerant and loss of the lubricant from the compressor, until finally the apparatus loses its efficiency to such a degree it becomes impractical.

The vaporized refrigerant is drawn from the low pressure side of the apparatus by means of the compressor 1, which is operated by any suitable motor 2. The refrigerant as a vapor at high pressure is directed into the condenser 3. The vapor gradually liquefies and collects in the reservoir 4 from whence it is forced through a pipe 5 into the valve casing 10 when the valve is opened to permit it to enter the casing, and from the casing it passes to one or more expansion or evaporative units, or heat absorptive units of the system.

The high pressure gas indicated in the coils 3 by the diagonal and more widely separated parallel lines 6, and the condensed or liquefied refrigerant is indicated by the closely diagonal parallel lines 7. The lubricant

used for lubricating the compressor becomes absorbed in, or caught up by, the refrigerant and is carried from the compressor as indicated by the vertical closely positioned parallel lines 8. Some lubricants will be dissolved in some refrigerants and thus distributed throughout the refrigerant. Other lubricants may have a specific gravity that is greater than the specific gravity of the liquefied refrigerant, in connection with which it is used, which will produce a tendency of the lubricant to settle within the liquefied refrigerant when at rest. Or, on the other hand, the density of the liquefied refrigerant may be greater than that of the lubricant which produces a tendency of the lubricant to float on the surface of the liquefied refrigerant when the liquefied refrigerant is at rest. Variations of these conditions, however, may occur in other refrigerants and lubricants. The lubricant, however, may be, in different parts of the apparatus, caught up by the vaporized or liquefied refrigerant and carried before it in confined passage-ways of the system.

In order that the refrigerant may efficiently perform its function of chilling, it is allowed to enter the expansion or low pressure side of the system progressively as the liquefied refrigerant, in the expansion side, is vaporized. In order to control this movement from one side of the apparatus to the other side, a releasing valve is located at the end of the pipe 5 which connects the reservoir 4 with the valve casing 10.

The pipe 5 is connected to the valve header 22 which constitutes a support for the various parts of the valve structure and the interconnecting means of a plurality of chilling units. Where one or more of such units are used, the valve header then forms a compact arrangement that may be made at a low cost of production and all of the controlling and sensitive parts of the apparatus may be mounted in a single unit and installed as such in the apparatus. Also, it provides a means whereby the apparatus may be readily repaired and the intercontrol between the parts of the apparatus may be readily adjusted according to the needs that may arise in the operation of the apparatus.

The pipe 5 is connected to the valve header 22 by suitable threaded bushings and sleeves, such as, the bushing 26 and the sleeve 28. The passage-way of the pipe 5 passes through the sleeve 28 and through a short pipe 29 that is connected to the sleeve 28. The lower end of the pipe 29 extends well into the chamber 25 that is formed, or drilled, in the valve header 22. A second pipe 30 extends to near the top of the chamber 25, so that the pipes 29 and 30 have over-extending portions. The chamber 25 in conjunction with the pipes 29 and 30 provide a trap for any water or dirt, and other extraneous matter that may exist in the refrigerant, or may be formed therein.

by reactions that may occur, and for any scale or metal particles that may collect from the inner surface of the apparatus in the operations of the system.

Preparatory to utilizing the apparatus, I have found, in the case of certain refrigerants, that it is desirable to provide for the removal of water because of its tendency to freeze in the refrigerant in the refrigerant part of the system which reduces the efficiency of the system and may prevent its operation. It is practically impossible to remove all of the moisture from the apparatus preparatory to the introduction of the refrigerant and, moreover, the refrigerant itself often is highly absorptive of water. When, therefore, the apparatus has been operating a short time, practically all of the moisture will be condensed and separated and collected in the chamber 25, and, if the moisture contained in the chamber 25 is removed, practically all of the moisture will be eliminated from the apparatus and from the refrigerant. I have provided a means for removing the moisture and other particles that will collect in the chamber 25. An opening is formed in the wall of the valve header 22 at the bottom of the chamber which extends from the outside of the header to a point near the inner surface of the chamber 25 and so as to leave a very thin wall between the inner end of the opening and the surface of the chamber 25. Preferably, the opening 19 is formed with a conical inner end having a relatively large altitude as compared to the base of the cone to the inner end portion of the surface of the opening 19. When, therefore, the apparatus has been running a short period, the low temperature that is maintained in the valve header, owing to the expansion of the refrigerant, will cause the moisture to be collected in the chamber 25 and will be, moreover, subject to the very high pressure that is created by the compressor. To remove the liquid and other material that may have collected in the chamber 25, a small hole is drilled at the apex of the conical surface through the thin separating wall portion and, owing to the very high pressure that the material within the chamber is subjected, it will be quickly blown out. A soft metal pellet is immediately rammed in to effectively seal the opening and is subsequently backed up with solder that is introduced in the opening 19.

The outlet of the chamber 25 is, preferably, located at its upper end to provide for the deposition and trapping of foreign material in the chamber 25 and the passage-way leads to a chamber 18, whose outlet is through a very small opening 17, that is controlled by the movable valve member 40. The ratio of the effective area of the passage-way of the chamber 25, to the opening 17, is such as to give a very slow velocity of the fluid through the chamber 25 to allow the deposition and

collection of foreign material in the chamber 25. Furthermore, the valve control opening 17 is protected by a screen 39 located in the chamber 18 which further prevents the movement of foreign material particularly foreign solid material, into the apparatus. The screen 39 is so located in the valve header 22 that it may be readily removed and cleaned of foreign material. Thus I have provided means in my valve header whereby the refrigerant may be kept clean from all foreign liquids and material that may act as a deterrent in the functioning of the refrigerant.

The chamber 18 is formed within a hollow cap screw 37 and a hollow retaining screw 36. The inner end of the chamber 18 being formed by the outer end of the removable valve seat and guide 35, which has the opening 17 that forms the outlet of the chamber 18. A tapped opening is formed in the header 22 and a smaller opening extends from the inner end of the tapped opening and concentric with the tapped opening to the inner side of the header 22. The valve seat or guide 35 is located at the bottom of the tapped opening and extends through the smaller opening 32 to the inside of the valve casing 10. The valve seat and guide 35 has a flanged portion 16 that forms a shoulder that is located against the end of the tapped opening and about the smaller opening 32. The valve seat and guide is also provided with a reduced cross-sectional area portion 15 that fits the opening 32 and extends a short distance in the opening 32, but not entirely therethrough. The inner end of the guide 35 terminates in a still further reduced cross-sectional area protruding portion 14, leaving an annular space between the portion 14 and the surface of the opening 32. The valve seat 13 is located in the portion 15 and at the inner end of the opening 17 and coaxial therewith an opening 12' is formed in the protruding portion 14, in which the movable valve member 40 is located. The protruding portion 14 forms a guide for the valve member 40. A slot 11' is cut from one side of the valve guide and seat 35 to a point on the opposite side of the opening 12'. The inner edge of the valve seat 13 is located at the surface of the slot 11' and so that as the valve member 40 is moved from the seat to open the opening 17, the fluid will have opportunity to freely flow from the confinement of the small opening 17 which immediately releases the pressure of the fluid as it escapes into the larger passage-way that is formed by the slot 11' and the space formed between the surfaces of the opening 32 in the header 22, and the cylindrical protruding guide 14 of the combined guide and valve seat 35. The reservoir 4 must have liquid enough to fill the coil 11 and the valve casing 10 to the depth normally deter-

mined by the valve 40 in its relation to the seat.

The valve guide and seat 35 is not only held in position by the fitting of the portion 15 in the opening 32, but also by the hollow retaining screw 36 which is threaded into the tapped opening that is formed in the header 22. The retaining screw 36 is castellated in order that it may be engaged with a suitable spanner wrench to lock the valve guide 35 in position. The screen 39 may be secured coaxial with the opening 17 in any desired manner. It is, preferably, spot welded to the outer face of the valve guide 35. The opening within the retaining screw 36 which forms a part of the chamber 18 has a diameter that is materially larger than the diameter of the screen 39 to allow free movement of the fluid that enters from the passage-way from the top of the chamber 25. Also, the opening in the hollow cap screw 37 has a diameter, preferably, substantially the same as that of the opening in the retaining screw 36, which completes the formation of the chamber 18 in which the screen 39 is located. The communication between the chamber 18 and the passage-way leading from the chamber 25 is through the slots of the castellated retaining screw 30 and the small space between the outer end of the retaining screw and the inner end of the cap screw. The tapped opening in the valve header 22 is sealed by means of a suitable gasket 38 located intermediate the valve header 22 and the flange of the cap screw 37.

The valve casing 10 is formed of the valve header 22 and the shell 20. The shell 20 may be a sheet metal pressed dome shaped container for enclosing the operative parts of the valve structure and forming a reservoir for the receipt of the liquefied refrigerant. The sheet metal dome shaped portion 20 is secured to the header 22, which is formed, preferably, of a forging to eliminate all possibility of blow holes, etc. The shell 20 has a flange 21 that is clamped between the ring 23 and the header by means of the machine screws 24 that are threaded into the header 22. Suitable soft metal gaskets may be located intermediate the flange 21 and the header 22, and also intermediate the flange 21 and the collar 23. Also suitable soft metal washers may be located below the heads of the machine screws 24 to maintain the gas tight seal of the shell 20. The inner surface of the valve header 22 and the surface of the flange 21 may be surface ground to coact with the interposed gasket to seal the interior of the valve casing 10. The entire construction is such that it may be submerged in a tin bath for perfect sealing of the entire assembly when the pipe connections are made.

The level of the liquid is controlled by a

liquid displacement member that operates the valve 40. The valve 40 slidably moves in the protruding portion 14 of the valve guide 35 and is connected to the displacement member 49 which is moved according to the quantity of the refrigerant liquid that is admitted through the opening 17 into the casing 10. The displacement member 49 has an arm 46 that is pivotally supported on the valve header 22. Preferably, the valve header 22 is provided with a bracket 41 that may be spot welded to the header 22. Preferably, the bracket 41 has an annular portion 42 that surrounds the opening 32 formed in the header 22 and so as to form a continuous exit from the chamber 18 as controlled by the valve member 40. The bracket 41 is provided with suitable nibs 48 between which the end of the arm 46 is connected by the pivot pin 47. The arm 46 is provided with a round headed lug 45 that fits an opening 43 formed in the head 44 of the movable valve member 40, so that as the displacement member 49 is raised and lowered, by changes in the level of the liquefied refrigerant in the casing 10 and the counterbalancing spring or springs 50, the lug 45 will operate as a crank to slidably move the valve member 40 in the valve guide 35 to close and open the small passage-way 17 as the valve member 40 is pressed against and removed from its seat.

The inner end of the valve member 40 is provided with a seat, or needle, 51 which extends substantially through the opening 17. If any particle of foreign material should enter the opening 17 that would, more or less, clog the passage-way through the opening, the seat 51 will displace it and keep the opening practically free for free movement of the fluid therethrough.

The arrangement of the valve support is such that it may be readily removed and its surrounding parts readily cleaned of any material that may collect therein and the valve seat may be adjusted with reference to the level of the liquid that is contained within the valve casing 10 and so as to modify, as desired, the regulative effect of the displacement member 49. When any adjustment is desired to be made, or when it is desired to inspect the operating conditions of the control elements of the valve, the screw cap 37 is removed and then the hollow retaining screw 36 is likewise removed, whereupon the valve guide and seat 37 may be withdrawn from its position in the opening 32. This leaves the movable valve member 40 free so that it may be lifted from the rounded lug 45 and withdrawn from the valve casing 10. The seat 13 may be then readily inspected through the slot 11 and the screen 39 may be cleaned, and, if desired, the level of the liquid at which the valve member is to be opened or closed

within the desired limits, may be adjusted or varied by the insertion of spacing gaskets 52 that may be located intermediate the head of the valve guide 35 and the valve header 22. The thickness of the gasket 52 will vary the location of the seat 13 with reference to the end of the valve 40 to vary the point at which the closure of the valve will take place upon the upward movement of the displacement member 49. The parts may then be returned or replaced after the desired cleaning and adjustment has been made. The end of the projecting part 14 is made conical in order that the end of the valve may be guided to the opening 12.

The refrigerant liquid in the valve casing 10 passes downward through the pipe 58, which is connected to the header 22 and enters the coil 11 which is also connected to the header 22 through the pipe 59. The passage-way in the header that communicates with the pipe 59, terminates in an outlet 61 which is located above the inlet of the pipe 58. The outlet 61 is, preferably, at the level of the liquid that is maintained by the displacement 49 in its control of the valve 40. The location of the outlet 61 may be varied as to its height as may be desired. Owing to the fact that the coil 11 absorbs a large quantity of heat from the surrounding medium, there is a constant change from the liquid to the gas within the coil 11 which causes a rapid circulation of the liquid through the coil. The openings, therefore, in the valve header 22, are made large so as to allow for the free circulation of the liquid and of the collection of the gas from the coil which rises through the header and enters the valve casing 10. As the liquid changes to the gas, its level is lowered within the valve casing 10, allowing an additional quantity of the liquid to enter the valve casing. As the liquid in the casing 10 and the coil 11 changes to a gas, the level of the liquid in the casing 10 is lowered thereby, which loss in level is compensated for by additional liquid refrigerant admitted to the inside of the casing 10 by the action of the displacement member 49 on the valve plunger 40.

If desired, the coil 11 may be entirely eliminated which will change it from what might be termed a wet evaporative system to a dry evaporative system or from a flooded system to an expansive system. The elimination of the coil 11 converts the system into a dry system, or an expansive system, for the reason that the system will be dependent for its operation on the evaporation and expulsion of the low pressure liquid contained in the valve casing. Thus, by my invention, it is possible to secure the advantages of a float chamber located on the low pressure side of a compression refrigerating system for admitting refrigerant

thereto with only a relatively small quantity of refrigerant.

The vaporized refrigerant passes through a pipe 55 which is provided with a plurality of openings 56. The openings 56 are, preferably, made small so that the pipe 55 will act as a baffle to prevent the entrance of liquid refrigerant into the pipe 55 in case of undue agitation of the liquid or the formation of foam in the valve casing 10. If desired, the pipe 55 may be provided with a baffle 57 located on the exterior of the pipe. The pipe 55 is connected to the header 22 and terminates near the pipe 66, that also extends in a bore 64, formed in the header 22. The diameter of the bore 64 is considerably larger than the exterior diameter of the pipe 66. The bore 64 extends well below the point of entrance of the pipe 55 in the header 22, and the pipe 66 extends to near the bottom of the bore 64. The pipe 66 has a very small opening 70 and the effective area of the communication through the opening 70 is adjusted by means of a threaded conical ended plug 74. A valve 67 is located on the exit end of the pipe 66 and is spring pressed, or loaded, by means of the spring 68 which operates to yieldingly resist the opening of the valve 67. Thus the gas will escape through the valve casing 10, the pipe 55 and the pipe 66, according to the pressure that is created in the valve casing as controlled by the valve 67. The pipe 66 is held in position by a flanged end which substantially fits the tapped opening and an elbow 65 is screwed into the tapped opening so as to clamp the flanged end of the pipe 66 and thus secure it in position coaxial with respect to the opening 64. The lower end of the opening 64, and the lower end of the pipe 66, will be closed by the refrigerant liquid during the idle compressor period in the cycle of the operations and the gas that comes from the pipe 55 will normally leak through the opening 70 as the pressure rises sufficiently to force open the valve 67.

A second coil 12 which, preferably, has a diameter much smaller than the coil 11, is connected to the elbow 65 through the pipe 71. In the coil 12 there is also the usual expansion and during the expansion there is also the usual absorption of heat. The gas then passes into the liquid refrigerant trap where it likewise absorbs heat from the surrounding medium by further expansion.

When the compressor is in operation, the vapor is drawn from the chilling units that may be contained in a suitable vat 14 and submerged, if desired, in any anti-freeze solution, such as brine, or water and alcohol, glycerine and water, etc., located in a suitable vat. This produces a low pressure in the trap and separator 13 and in the coil 12. This in turn draws the vapor from within the valve casing 10 and causes rapid evap-

oration of the liquefied refrigerant that is contained in the valve casing 10. It also draws any liquid that may collect in the bore 64 of the header 22. Also, the lower end of the bore 64 is connected with the bottom of the casing 10 by means of the pipe 63 which is covered at its outer end by means of a sieve 62 which, together with its outer end, lies on the bottom, or substantially at the bottom, of the valve casing 10. Thus the liquid contained in the valve casing 10 will be drawn through the opening 73 into the bore 64 by the suction produced by the compressor, and will pass through the coil 12 and into the lubricant and liquid refrigerant trap 13. Also, if it is desired to draw the liquid from the coil 11, the pipe 63, shown in Fig. 4, may be extended from the opening 73 into the pipe 58 and downward through the pipe 58 to the lower end of the coil 11, shown in Fig. 13, where the sieve 62 may be used to strain the liquid that passes into the pipe 63, and upwards and into the bore 64.

There will be thus produced a uniform circulation of the refrigerant and also there will be maintained a uniform dissemination of the lubricant throughout the refrigerant. The liquid mixture will be caught in the trap 13 where opportunity will be given for the refrigerant to vaporize and the lubricant to progressively separate from the refrigerant and finally enter in subdivided portions at a uniform rate into the vapor which is drawn through the trap and also that which is formed in the trap.

The trap 13 may partake of a variety of forms. The trap shown in the drawings is a cylindrical sheet metal container having a plurality of cups 80 that will entrap the liquid that enters through the pipe 12. Each of the cups 80 are provided with a flanged opening located in its bottom, the flange of the opening extending to near the level of the top edge of the cup. In order to prevent free flow of the liquid that may enter through the pipe 12, into the trap 13, the flanged openings are suitably staggered, one relative to the other as shown in Fig. 3. If desired, the flanged openings may be centered and made conical in form so as to guide the overflow of the liquid to one side of the flange of each lower cup and thereby trap the overflow in the next lower cup. Also, the flanged openings within the trap 13 permit the free movement of the vapor through the trap 13 and the low pressure created by the compressor 1, that is transmitted through the pipe 84, causes the vaporization of the refrigerant located within the cups and the vapor that is thus formed will pass through the flanged openings into the pipe 84 and to the compressor 1.

The cups are provided with openings 82 located in the bottoms of the cups which allow the lubricant and some of the liquid re-

frigerant slowly to drain from each cup into the succeeding cup. As the liquids progress, the refrigerant is evaporated until finally from the last cup the lubricant will drip into the space that communicates with the pipe 84, and so that it will be gradually and progressively collected and snatched by the vapor through the pipe 84 into the compressor, thereby uniformly directing the separated lubricant to the compressor.

The liquid retaining means may partake of different forms, a single cup of considerable diameter may be used, or a plurality of cups may be utilized, the object being to trap the mixture of liquids that pass from the coil 12 and until they are separated by distillation, or by over- or under-flow of one of the liquids.

In the particular form of construction shown in Fig. 3, a plurality of cups are used and each of the cups are provided with flanged openings 81, and also are provided with minute openings 82. The flanged openings 81 permit the movement of the liquids through the cups by its overflowing the flanges and also permits the movement of the vapor, that is created by the suction of the compressor, while the openings 82 permit the gradual movement of the lubricant from one cup to another and finally from the lower-most cup into the vapor that is being drawn to the compressor.

In the form of cup shown in Fig. 11, the flanged opening is conical in form which will direct the overflow down the upwardly sloping surface and so that it will be caught by the cup below. One advantage of the form of cup shown in Fig. 11, the movement of the vapor through the cup will tend to blow the liquid in all directions away from the flanged opening, and thus insure that each succeeding cup will be filled with the liquid contained in the fluid that is being drawn through the trap by means of the compressor. The fluid is largely a mixture of refrigerant vapor, refrigerant liquid and, more or less foamy or vaporous liquid lubricant and refrigerant.

In the form of cup shown in Fig. 12, the cup is made somewhat crescent shaped and the side wall of the cup forms its flanged outlet at one side of the cup and between the side of the cup and the wall of the container, or trap 13. The openings that are thus formed by the shape of the cup, with reference to the wall of the trap 13, are also staggered with reference to each other in the same manner that the openings of the cups shown in Figs. 3 and 10 are staggered relative to each other, and so as to trap the liquids that may be carried by the fluids that are drawn by the compressor from the chilling units of the apparatus.

The construction of the coil 12 and the trap 13, must be of such a character that they

will cause the evaporation of substantially all of the liquid refrigerant that may be drawn into these parts by the compressor, and this evaporation should take place during the period in which the compressor is in operation.

During this operation of the compressor, there is a tendency to produce a considerable agitation within the valve casing 10 and, in order to prevent agitation of the liquid contained in the valve casing 10 from unduly affecting the displacement member 49, a plurality of baffles 90 may be located within the wall of the valve casing 10 and so as to surround the displacement member 49 and yet be spaced therefrom sufficiently to prevent any interference with the operation of the displacement member in its control or action of the movable valve member 40. Also, the baffles 90 will prevent too free movement of the froth that may exist in the valve casing 10, through the pipe 55, when the compressor is in operation.

I claim:

1. In a compression refrigerating system, a compressor, a plurality of chilling units connected in series to the compressor, a liquid level responsive release valve for admitting liquefied refrigerant to the first of the said chilling units, a divided passage for admitting vapor through one part of the divided passageway from the first chilling unit to the second chilling unit during the slow evaporative period of the operation of the refrigerating apparatus and liquefied refrigerant at a predetermined rate during the compression period of the operation of the apparatus through another part of the divided passageway.

2. In a compression refrigerating system, a compressor, a refrigerating unit, a valve casing having a valve header, a release valve located in the valve casing and supported on the valve header for admitting liquefied refrigerant into the refrigerating unit, the inlet and the outlet of the refrigerating unit connected to the valve casing through the valve header, a trap communicating with the valve casing through the valve header, a trap communicating with the valve casing through the valve header, a trap communicating with the valve casing through the valve header for retaining the liquefied refrigerant and the lubricant until the refrigerant has evaporated and the lubricant is discharged in the evaporated refrigerant.

3. In a compression refrigerating system, a compressor, a valve casing having a valve header, a release valve located in the casing and supported on the header for admitting liquefied refrigerant into the valve casing, the header having a chamber located in the header and intermediate the compressor and the valve, the header having a bored portion, and a thin wall for separating the bored portion from the chamber whereby material may

be removed from the refrigerating apparatus.

4. In a compression refrigerating system, a compressor, a valve casing having a valve header, a release valve located in the casing and supported on the header for admitting liquefied refrigerant into the valve casing, the valve header having a chamber in the passage-way leading to the valve seat and a screen located in the chamber and surrounding the inlet controlled by the valve.

5. In a compression refrigerating system, a compressor, a refrigerating unit, a valve casing having a valve header, a release valve located in the valve casing and supported on the valve header for admitting liquefied refrigerant into the refrigerating unit, the inlet and the outlet of the refrigerating unit connected to the valve casing through the valve header, a trap communicating with the valve casing through the valve header.

6. In a compression refrigerating system, a compressor, a liquid refrigerant container, a chilling unit, a level controlled release valve located intermediate the container and a chilling unit and controlled by the level of the liquid in the container for controlling the movement of the liquefied refrigerant to the chilling unit, a second valve located between the container and the chilling unit for maintaining the pressure in the container greater than that in the chilling unit.

7. In a compression refrigerating system, a compressor, a plurality of chilling units surrounded by a common medium, a liquid level responsive releasing valve in the first chilling unit, a second valve located between the first chilling unit and the other chilling units, a passage-way having a restricted opening located in advance of the last named valve for controlling the movement of the refrigerant fluid to the last named valve.

8. In a compression refrigerating system, a compressor, a liquid refrigerant reservoir for receiving the liquefied refrigerant from the compressor, a valve casing having a valve header connected to the reservoir, a valve member located in the header for admitting refrigerant liquid to the valve casing from the reservoir and controlled by the level of the liquid refrigerant in the casing, the header having a well, the lower extremity of the well located below the level of the liquid in the casing, the well communicating with the casing at two points, one communicating with the casing above the level of the liquid and the other communicating with the casing below the level of the liquid, and a refrigerating unit connected to the well at a point near the bottom of the well.

9. In a compression refrigerating system, a compressor, a liquid refrigerant reservoir for receiving the liquefied refrigerant from the compressor, a valve casing having a valve header connected to the reservoir, a valve

- member located in the header for admitting refrigerant liquid to the valve casing and controlled by the level of the liquid refrigerant in the casing, a well located in the header having its lower extremity located below the 5 level of the liquid in the casing, the well communicating with the casing at two points, one communicating with the casing above the level of the liquid and the other communicating with the casing below the level of the 10 liquid, a refrigerating unit connected to near the bottom of the well, and a bleeder opening in the connection of the well with the refrigerating unit.
- 15 10. In a compression refrigerating system, a valve casing having a valve header, a float located in the casing, the valve header having an opening, a valve member located in the header and controlled by the level of the 20 liquid refrigerant in the casing, a removable plug for closing the opening, the valve member removably connected to the float, a valve seat located in the plug, whereby the valve member and the plug may be withdrawn through the opening in the header without 25 displacement of the float.

In witness whereof I have hereunto signed my name to this specification.

PHILIP W. DES ROCHES.
